UNITED STATES PATENT OFFICE.

ARTHUR G. REIMERS, OF MILWAUKEE, WISCONSIN, ASSIGNOR TO UNDERWOOD ELLIOTT FISHER COMPANY, OF NEW YORK, N. Y., A CORPORATION OF DELAWARE.

TYPEWRITING MACHINE.

Application filed March 30, 1929. Serial No. 351,215.

The present invention relates generally to ribbon-vibrating devices for front-strike typewriting machines, and more particularly to avoiding faulty operation of such devices at high speed.

In a front-strike typewriting machine, shortly before the type-bar reaches the platen, the former engages a universal bar, which causes a mechanism to vibrate the ribbon upwardly in front of the printing point. It is desirable in typewriter-construction to reduce the power required for vibrating the ribbon, since this power is created by the pressure of the operator's fingers on the typewriter-keys, and every reduction in the power required for vibrating the ribbon makes for a lighter "touch" for the typewriting machine. Furthermore, in rapidly operating a typewriting machine, such as the Underwood, which is widely used for high-speed work, the operator's fingers, when depressing the keys, frequently do not complete the stroke or "follow through", and the impact of the type against the platen is then dependent upon the momentum of the type-bar. It is important that the ribbon-vibrating mechanism operate properly, otherwise any retarding action, such as may be caused by gumming and undue friction, will act through the unyielding connection of the vibrating mechanism and the type-bar, to bring a braking action, so to speak, on the movement of the type-bar, and a weaker impact of the type against the platen will result therefrom.

Free movement of the ribbon-vibrator in an Underwood typewriting machine is sometimes found to be retarded by detritus from erasures lodging between the ribbon-vibrator and the rear face of a fixed segment-member against which the vibrator slides up and down. It has been the practice to oil the vibrator, yet it is found to have occasional faulty action at high speeds. In some instances the vibrator stays in its top position, and has other erratic tendencies.

A feature of the present invention resides in the provision of a ribbon-vibrator having means to prevent the accumulation of such friction-creating matter between it and the

fixed segment, thereby overcoming these faults. In carrying out this feature, discharge holes are made in the body of the ribbon-vibrator and spaced along its longitudinal axis. To make these holes more efficient in discharging such matter, it is a further feature of the invention to have the holes flared rearwardly, that is, away from the segment. These holes further conduce to efficiency of lubrication, without incurring the former trouble of adhesion between the vibrator and the segment, due to the oil.

Other features and advantages will hereinafter appear.

In the accompanying drawings,

Figure 1 is a fragmentary front view of an Underwood typewriting machine having the present invention applied thereto.

Figure 2 is a fragmentary cross-sectional view, from front to rear, through the structure shown in Figure 1.

Figure 3 is a rear perspective view of the structure shown in Figure 1.

In an Underwood standard typewriting machine, to which the present invention may be advantageously applied, each type-bar 10 carries types 11, either of which, upon depression of an associated key (not shown), may be swung against a platen 12, which is mounted on a shaft 13, journaled in a usual platen-frame (not shown).

An ink-ribbon 14, carried on two usual ribbon-spools 15, is moved upwardly in front of the printing point just before each type strikes the sheet W on the platen. The ribbon 14, in front of the printing point, is supported on a ribbon-guide 16. The upper end portion of the guide is formed with forks 17, one fork on each side of the printing point.

To secure against lateral displacement, each fork 17 has a guide-finger 18, which engages the side of a usual vertically-disposed type-guide 20, which is mounted on the usual segment 21, rigidly fastened to the frame 22 of the machine.

The ribbon-guide includes a body 23, whose lower portion is arranged in two forks 24, whose lower end portions are curled around a pin 25, which extends across a lengthwise slot 26 in the body 23.

The usual ribbon-vibrator lever 27 is pivoted upon a pin 28, and may be rocked by a universal-bar device (not shown), which may selectively engage either of two fulcrum-pins 29, 30 in a manner substantially as set forth in Patent No. 926,050, granted to F. A. Cook, June 22, 1909.

It can be seen from inspection of Figures 2 and 3 that the ribbon-guide 16 slides up and down between the usual fixed guide-plate 31 and a face of the fixed segment 21 almost vertically under the printing point. This arrangement makes it possible for small bits of rubber, paper, or other erasing detritus to lodge between the ribbon-guide and the segment. This detritus heretofore has not always been quickly discharged or removed, and consequently sometimes caused a retarding action and faultiness in the movement of the ribbon-guide mentioned above.

It is a feature of the present invention to arrange for immediately removing bits of rubber and other erasure detritus which may lodge between the ribbon-guide 16 and the segment 21, by providing, in the body of the ribbon-guide, a plurality of openings 32, which are spaced along the longitudinal axis of the body 23 of the ribbon-guide, and two smaller holes 33, one at each side of the axis, adjacent the lower end of a usual bifurcating slot 34, whose lower end terminates substantially even with the top of the segment 21. It can be seen by inspection of Figures 1 and 3 that the apertures 33 co-operate with the slot 34 to help prevent detritus, etc., from passing downwardly between the body 23 and the segment 21. To further increase the efficiency of the holes 32, 33, in discharging detritus quickly, they are flared rearwardly, as illustrated in Figure 2, and it can be readily seen that a bit of detritus finding its way into one of the holes will immediately roll away from the face of the segment 21.

The holes 32 also provide another advantage. Heretofore, when the ribbon-guide 16 was given an excess of unsuitable lubrication, there sometimes resulted a kind of adhesion or mild suction between the body 23 of the ribbon-guide and the segment 21, which operated to slightly hinder the free movement of the ribbon-guide. The holes 32 will greatly reduce any such suction.

It will be noted that the holes 32, besides providing the advantages described above, at the same time, reduce the weight of the ribbon-guide 16 a relatively large amount, which is desirable.

Variations may be resorted to within the scope of the invention, and portions of the improvements may be used without others.

Having thus described my invention, I claim:

1. In a front-strike typewriting machine having a platen and a fixed member with an upright surface below the printing point of

said platen, a vibrating ribbon-guide sliding against said surface, said guide having a plurality of apertures through it, extending from its side adjacent said member through the opposite side, said apertures arranged for removing detritus lodging between said ribbon-guide and said surface.

2. In a typewriting machine having a revoluble platen, the combination with a fixed member of said machine disposed below the printing point of said platen and having an upright surface, of a ribbon-guide moving up and down against said surface, said guide having a plurality of apertures through it arranged for discharging friction-causing detritus accumulating between said ribbon-guide and said member.

3. In a front-strike typewriting machine having a platen and a fixed member with an upright surface below the printing point of said platen, a ribbon-guide moving up and down against said surface, said guide having a plurality of holes through it, extending from its side adjacent said member through the opposite side, said holes arranged for discharging detritus lodging between said ribbon-guide and said surface, and said holes being flared away from said surface for quickly discharging detritus disposed therein.

4. In a front-strike typewriting machine having a platen and a fixed member with an upright surface below the printing point of said platen, a ribbon-guide vibrating up and down against said surface and having a forked upper portion formed by a bifurcating slot extending downwardly substantially to the top of said member, said ribbon-guide having two apertures through it, one spaced on each side of said slot adjacent the lower end thereof, and a plurality of additional lower apertures spaced along the length of said ribbon-guide, said apertures extending from the face of said ribbon-guide adjacent said member through the opposite face for the purpose specified.

ARTHUR G. REIMERS.
